Primary Examiner — Ricky Pham(74) *Attorney, Agent, or Firm* — Browdy and Neimark, PLLC(57) **CLAIM**

The ornamental design for a toaster oven, as shown and described.

DESCRIPTION

FIG. 1 is a perspective view of a toaster oven according to the present design;

FIG. 2 is a perspective view thereof with the lid opened;

FIG. 3 is a front view thereof;

FIG. 4 is a rear view thereof;

FIG. 5 is a left side view thereof;

FIG. 6 is a top plan view thereof; and,

FIG. 7 is a bottom view thereof.

The right side of the toaster oven according to the present design is a mirror image of the left side view.
